[57] CLAIM

The ornamental design for a golf putter head, as shown and described.

DESCRIPTION

FIG. 1 is a perspective view from the top showing our new design;

FIG. 2 is a perspective view from the bottom;

FIG. 3 is a top plan view;

FIG. 4 is a front elevational view;

FIG. 5 is a right side elevational view;

FIG. 6 is a rear elevational view; and,

FIG. 7 is a bottom plan view.

The broken line showing of the fragmented shaft in FIG. 1 is for illustrative purposes only and forms no part of the claimed design.

The left side elevational view is a mirror image of the right side elevational view.
